UNITED STATES PATENT OFFICE.

CHARLES H. NORRLIN, OF PHILADELPHIA, PENNSYLVANIA.

AUTOMOBILE RADIATOR.

Application filed July 24, 1923. Serial No. 653,546.

To all whom it may concern:

Be it known that I, CHARLES H. NORRLIN, a citizen of the United States, and resident of Tacony, Philadelphia, in the county of 5 Philadelphia and State of Pennsylvania, have invented certain new and useful Improvements in Automobile Radiators; and I do hereby declare the following to be a full, clear, and exact description of the invention, 10 such as will enable others skilled in the art to which it appertains to make and use the same.

This invention relates to means for cooling or condensing fluids and has particular 15 reference to radiators for motor vehicles and other mechanisms dependent for efficient and economical operation upon means for cooling or condensing steam or other vapor. One object of the invention is to 20 provide a simple and inexpensive structure wherein the fluid to be cooled or condensed will be caused to flow in a thin film over a tortuous path to give off its heat, and another object is to provide for an efficient 25 circulation of air across and about the path of the fluid. Other objects of the invention are to provide a radiator of few parts, to provide means for maintaining the spaced 30 relation of the walls of the fluid passage, and to effectually close all joints. Other objects will appear incidentally in the course 35 of the following description.

In the annexed drawings, which illustrate one embodiment of the invention, Figure 1 is a front elevation of a radiator containing my improvements; Figure 2 is an end elevation of the same; Figure 3 is a vertical front to rear section taken principally on the central line of the radiator; 40 Figure 4 is a detail section on the line 4—4 of Figure 3; Figure 5 is a detail section on the line 5—5 of Figure 4; Fig. 6 is a detail front to rear vertical section of a portion of the front wall of the radiator on the line 45 6—6 of Fig. 1.

Fig. 7 is a similar view of the rear wall.

Fig. 8 is a detail transverse section on the line 8—8 of Fig. 7.

In carrying out my invention, I employ 50 two sheets 1, 2 of metal or other suitable material pressed or folded into a sinuous or corrugated form so that they may be fitted together, as shown in Figure 3, with the alternate bends or bights of one sheet fitting 55 within bends or bights of the other sheet. A narrow space 3 is thus formed between

the two sheets through which the water or other fluid may flow in a thin film from which the contained heat may readily and rapidly escape, and it will be readily noted that the formation provides a large radiating surface within a relatively small cubic space. It will, of course, be understood that the corrugations may be provided in any desired size, shape or number. The side edges of the sheets 1 and 2 may be joined in any convenient manner and I have illustrated a desirable method in which the edge of the sheet 2 is crimped or compressed, as at 4, against the adjacent edge portions of 70 the sheet 1 which is folded or doubled outwardly to form a reentrant flange 5 housing the edge of the sheet 2. The flange may be folded or compressed tightly upon the crimped edge but soldering or brazing of 75 the joint will insure against leakage. To maintain the desired spaced relation of the sheets 1 and 2, ruffles 6 may be formed in or on the inner surfaces of the sheets at intervals to bridge the space between the sheets 80 and serve as braces to prevent collapse of the sheets. As shown most clearly in Figs. 7 and 8, the ruffles are produced by forming longitudinal depressions in one wall of the radiator between the bend thereof when the sheet material is stamped into form. As a 85 matter of economy and convenience, the ruffles or depressions are formed only on the rear wall or sheet 2. When the two sheets or walls are assembled, the ruffles come in contact with the wall and serve to maintain the proper spaced relation of the two walls or sheets, preventing them from collapsing and closing or obstructing the fluid passage.

To provide for ample free circulation of 90 air through the radiator, I form openings 7 through the several bends or bights of the fluid chamber at frequent intervals throughout the same. The walls of these openings may be defined by extending portions of the inner sheet into abutting relation to the outer sheet, as at 8, and pressing the outer sheet inwardly in the form of a nipple 9 fitting snugly within the extended portions 100 of the inner sheet. The joint may be sealed by brazing or soldering. Between the air openings or passages, I expand the bends or bights of the sheets, as at 10, to equalize the space and compensate for the loss of capacity due to the provision of the nipples 9.

The terminal portions of the sheets 1 and 2 are flared centrally toward their edges, as

at 11 and 12, thereby forming spouts or nozzles to be coupled to the inlet fitting 13 and the outlet fitting 14 respectively, the inlet fitting being constructed with a filling branch 15. The spouts or nozzles 11 and 12 are fitted snugly in the proper openings or branches of the fittings 13 and 14 and the outside joints are sealed with solder, as at 16, the fittings being connected with the water-circulating system in the usual manner. It is to be understood, however, that the sheets 1 and 2 may be formed or joined into similar manifolds.

From the foregoing description, taken in connection with the accompanying drawings, it will be seen that I have provided a radiator consisting essentially of two mating sheets of material secured together to form a chamber or tubular tortuous passage through which the fluid will flow in a thin film. It will also be noted that the construction permits the air to strike the walls of the radiator in a wide sheet and play at once upon a large surface area. The device is exceedingly simple and effective and may be very economically produced.

Having fully described my invention, what I claim as new and desire to secure by Letters-Patent, is:—

- 30 1. A radiator consisting essentially of two mating sheets of counterpart corrugated form secured together along their side edges to define a wide shallow tortuous passage for fluid, the bights of the corrugations being disposed transversely to the air flow.
- 35 2. A radiator consisting essentially of two sheets of corrugated material fitted together with the alternate bights of one sheet within the alternate bights of the other sheet, the side edges of the sheets being connected by sealed joints, and the bights of the sheets extending transversely to the air flow whereby the entire area of the front sheet is presented to the cooling medium.
- 40 45 3. A radiator consisting essentially of two mating sheets of corrugated material

secured together with the corrugations of one sheet fitting within the corrugations of the other sheet, there being air-circulating passages through the bights of the sheets closed to the space between the sheets and the corrugations extending transversely to the air flow whereby the entire area of the front sheet is presented to the said flow.

4. A radiator consisting of mating spaced corrugated walls defining a tortuous passage for liquid, the walls having openings through each corrugation at intervals, the inner wall at each corrugation having portions extending from the openings and abutting the outer wall, and nipples projected from the outer wall through the respective openings in the inner wall and defining air passages sealed to the space between the walls, the corrugations being transverse to the air flow.

5. A radiator consisting of mating corrugated walls secured together at their side edges and defining a shallow tortuous passage for fluid, and having openings through their corrugations, and nipples projecting from one sheet and sealed in the other sheet at said openings to define air-circulating passages, the corrugations of the sheets being expanded between said passages and being disposed transversely to the air flow.

6. A radiator consisting of mating corrugated sheets secured together at their side edges to define a shallow tortuous passage for fluid, the corrugations being transverse to the air flow and the end edge portions of the sheets being in divergent relation to form flared spouts for attachment to inlet and outlet fittings.

In testimony whereof, I have signed this specification in the presence of two subscribing witnesses.

CHARLES H. NORRLIN.
